UNITED STATES PATENT OFFICE.

CLARENCE W. CARTER, OF MINNEAPOLIS, MINNESOTA, ASSIGNOR TO CARTER-MAYHEW MANUFACTURING COMPANY, OF MINNEAPOLIS, MINNESOTA, A CORPORATION OF MINNESOTA.

GRAIN SEPARATOR.

Application filed February 26, 1923. Serial No. 621,235.

To all whom it may concern:

Be it known that I, CLARENCE W. CARTER, a citizen of the United States, residing at Minneapolis, in the county of Hennepin and

5 State of Minnesota, have invented certain new and useful Improvements in Grain Separators; and I do hereby declare the following to be a full, clear, and exact description of the invention, such as will enable others 10 skilled in the art to which it appertains to make and use the same.

My invention has for its particular object the provision of an extremely simple and highly efficient separator for the removal of 15 what is known as "dockage", from grain samples, and to such ends, generally stated, the invention consists of the novel devices and combinations of devices hereinafter described and defined in the claims.

20 Grain as it comes from the thrashing machine always contains more or less wild oats, wild peas, cockle, wild mustard, and various other foreign seeds and substances which, collectively, are known as "dockage." At 25 elevators, mills and other places where this grain is purchased, it is the established practice to take from the cars small samples, the standard being approximately one quart, and by the use of hand-operated sieves or

30 other separating means, to separate the dockage from the good grain to thereby determine the grade or value of the grain. By the means hitherto employed for the removal of dockage, it has been impossible to 35 get anywhere near all of the dockage or foreign substances out of the good grain and the amount remaining in the grain has varied, depending on the time employed in the separation and the manner of manipulation itself, so that it has hitherto generally

40 happened that when the same samples, or samples taken from the same body of grain, have been tested by different persons, the results have been different. Obviously, a 45 standard whereby the same grain will always be given the same grade or value is highly desirable.

In the first place, my invention provides 50 an extremely efficient dockage separator, and in the second place, I provide in connection therewith a motor or propelling means that will operate the separator for a predetermined time, say one minute or less, but which will be sufficient to separate sub- 55 substantially all of the foreign materials from

the wheat. With this arrangement, therefore, two samples separated at different places by two different machines of the same kind will give the same results.

The nature of this invention will be more 60 clearly apparent after having first described the same in connection with the accompanying drawings, wherein like characters indicate like parts throughout the several views.

Referring to the drawings:

Fig. 1 is a side elevation with some parts 65 broken away and some parts sectioned, showing the improved separator and means for driving the same;

Fig. 2 is a horizontal section taken approximately on the line 2—2 of Fig. 1, some parts being in full;

Fig. 3 is a rear elevation of the separator shown in Figs. 1 and 2;

Fig. 4 is a front elevation of the separator 70 shown in Figs. 1, 2 and 3, some parts being broken away and some parts being sectioned; and

Fig. 5 is a view corresponding to Fig. 1, 75 but illustrating a modified form of the separator, some parts being broken away.

The preferred form of the separator shown in Figs. 1, 2, 3 and 4 will first be described.

In this form of the separator, all of the 80 parts of the separator proper are supported on a suitable anchored pedestal 6, the upper end of which, as shown, is forked to afford axially aligned bearings 7, 8 and 9. A shaft 10, equipped at its outer end with a driving 85 sheave or pulley 11, is journaled in the bearings 7 and 8 and between said bearings is provided with a beveled pinion 12 which, as shown, is of the toothless or friction wheel type. Stub shafts 13 are journaled in the 90 bearings 8 and 9, and to the inner ends of these are rigidly secured the prongs of a forked arm 14, which, at its extended end, is formed with a heavy weight or head 15. Normally, the weighted head 15 rests on the 95 oblique portion of the pedestal 6. A fixed spindle 16 is rigidly secured at one end to the arm 14 and projects centrally therefrom between the prongs of said arm and preferably in a plane that includes the axes of 100 the stub shafts 13. The stub shafts 13, it will be noted, are axially aligned with each other and with the drive shaft 10. Mounted to rotate on the spindle 16 is a separating 105 drum that is open at one side and closed at 110

the other. This drum, as preferably designed, comprises a cylindrical body shell 17, an outwardly converging or contracted annular rim 18 at one side, and a solid head 19 at the other side, the said elements 17, 18 and 19 being rigidly connected. The head 19 at its axis is provided with a bearing sleeve 20 that is journaled on the spindle 16 and extends into the fork of the arm 14 so that the head 19 is arranged to run close to the bearings 7, 8 and 9. On its outer side, adjacent to its rim, the head 19 is formed with a bevel gear 21, which, as shown, is a toothless or friction surface arranged to run in frictional contact with the beveled friction pinion 12. The cylindrical drum shell 17 is formed with closely adjacent internal pockets 22 that are, for example, of a size to receive wheat kernels but are not long enough to receive oats. Mounted on the extended portion of the spindle 16 is a non-rotary but tiltable collecting hopper 23 provided at its outer end with a projecting discharge spout 24 that is normally closed by a spring-pressed gate 25.

The hopper 23 is preferably made readily detachable from the spindle 16 but is held against rotation thereon by a device shown in Figs. 1, 2 and 4, and which comprises a lock plate 27 mounted to slide in vertical guide flanges 26 on the outer end of the hopper. This lock plate 27 is provided with a perforation 28 having a contracted upwardly extended portion 29. The perforation 28 is large enough to pass the end of the spindle 16 therethrough and said spindle, at opposite sides, has vertically cut notches 30 that adapt the lock plate to be forced down onto the same, as best shown in Fig. 4, thereby locking the hopper both against axial and rotary movements on the spindle. When the lock plate 27 is raised, the hopper may be readily slid off from the spindle. It is also important to note that when the hopper is locked in position, the separating drum, while free for rotation on the spindle, will be held against axial sliding movement on said spindle.

The weighted head 15 is heavy enough to hold the separating drum and hopper, even when loaded with grain, in horizontal position or substantially as shown in Fig. 1. The rotary drum may be driven by various different means but is preferably driven from a spring motor 31, the rotor shaft of which is equipped with a small driving sheave or pulley 32, over which and the sheave 11 a driving belt 33 is arranged to run, said belt being indicated by dotted lines only. The spring motor 31 may be of any suitable or approved type, which, when wound up, will run and drive the separating drum for a predetermined interval of time. In practice, it has been found that less than a minute will be sufficient to ac-

complish the proper separation. As shown, said motor is provided with a winding crank 31^a shown by dotted lines in Figs. 1 and 2. To make the whole device a complete self-contained machine, capable of being moved from one place to another without requiring reassembling of parts, the pedestal 6 and the case of the motor 31 are secured to a common base 6^a or otherwise rigidly connected. 75

One of the important features of this invention is in the facility with which the separating drum may be applied in working position and removed. This makes possible the substitution of one drum for the other or the interchangeable use of drums having internal pockets of different sizes. For the separation of the wheat out of the commingled mass, the internal pockets of the separating drum should be of a size to receive wheat kernels but not long enough to receive the oats, but for the separation of the smaller seeds from the wheat, the separating drum should have pockets large enough only to receive the seeds smaller than the wheat and not large enough to receive the wheat kernels. 90

In the use of this separator for the separation of the dockage from the wheat, a commingled mass will be placed in a separating drum having pockets of a size to receive wheat kernels but not long enough to receive the oats. Then, under rotation of the drum, the wheat kernels will get into the pockets 22 and will be carried upward to points where they will slide out of said pockets, under the action of gravity, and will fall into the collecting hopper 23, but the oat kernels, being too long to get into the selecting pockets, will be rejected thereby and, under the action of gravity, will be caused to continuously roll or slide back toward the bottom of the drum. When the drum has been rotated long enough, to wit: a minute or less, substantially all of the good wheat kernels will be taken out of the oats and deposited in the hopper and the oats will remain in the drum. However, the small seeds and broken wheat kernels will be carried with the good wheat into the hopper. 100

By pressing downward on the spout 24 or on the outer portion of the hopper or drum, the weight 15 may be readily overcome and the hopper and drum tilted into the oblique position indicated by dotted lines in Fig. 1. In this position, the oats will run from the open end of the drum and may be discharged into a receptacle 34 placed below the same, but the wheat will be held within the hopper by the spring-pressed gate 25. If desired, the drum may be rotated while tilted, to facilitate the discharge of the oats therefrom, and this driving action in the tilted position is made possible because the drum 115 120 125 130

is tilted on the common axis of the driving pinion 12, drive shaft 10, and stud shafts 9.

After the oats have been discharged from the drum, another receptacle can be placed 5 below the discharge spout 24, and when the gate 25 is then opened, the wheat will run into this latter noted receptacle. By the operation just described, the oats are separated from the wheat but the wheat will be commingled with more or less small seeds and the like. To separate the small seeds and the like from good wheat, another drum just like the one described but having smaller pockets, as above indicated, will be placed 10 in working position and the wheat with these smaller seeds commingled therewith will be placed in this second separating drum thus substituted. Then, under rotation of the said drum, the small seeds, broken wheat 15 and the like will get into the pockets and will be carried upward and discharged into the hopper, while the wheat will slide or roll back towards the bottom drum. In this way, only good clean wheat will be left in 20 said drum and, of course, the separation thus effected may be obtained by the independent discharge of the seeds from the hopper and the wheat from the drum.

The fact that the drum is journaled and 25 supported at its closed side and free at its open side and also the fact that the hopper is carried on a spindle that is supported only at the same end or side of the device, 30 is highly important and such construction 35 is particularly feasible in a small separator of the character above described.

The conical or outwardly converging annular flange 18 is highly important because 40 it contracts the open side of the drum so that the oats will be retained in the drum throughout the separation action and the 45 outward convergence or truncated conical form of this flange is important because it facilitates the discharge of the oats when the drum is tilted. The drum head 19 has 50 been described as a closed head, but it is not essential that it be absolutely solid from hub to rim. It is, however, important that the outer portion of said head be imperforate so that that outer portion and the annular flange 18 form contractions at the 55 ends of the drum, serving to hold the commingled separable mass against travel axially of the drum. This arrangement is especially important in a small sample or 60 dockage tester where a continuous separating action is not desired but where the small batch is simply separated while being subjected constantly to the same separating action.

In the modified construction illustrated in Fig. 5, neither the drum nor the hopper is mounted for tilting movements. The drum here illustrated is of the same construction 65 as that previously described, except that, in

lieu of the frictional bevel gear 21, it is provided with a large driving sheave 35 located just outward of its fixed head and connected to said fixed head and having a sleeve that constitutes a hub portion of 70 said head. The spindle 36, which is otherwise like the spindle 16, is in this construction directly secured at one end to the upper end of a fixed pedestal 37. For the discharge of the oats from the drum, after the 75 separation has been made, the cylindrical surface of said drum is provided with a normally closed trap door 38. The hopper 39, in this arrangement, has an oblique bottom and an oblique discharge spout 40, 80 which latter is normally closed by a spring-pressed gate 41.

For driving the drum just described, I 85 preferably employ a small spring motor 42, the rotor shaft of which is provided with a small driving sheave 43, over which and the sheave 35 runs a driving belt 44 shown by dotted lines only in Fig. 5.

In the operation of the separator just 90 described and illustrated in Fig. 5, the oats will remain in the drum and the wheat will be carried into the hopper 39, and after the separation has been completed, the wheat can be drawn off from the hopper under 95 the action of gravity when the gate 41 is opened, while the oats may be discharged from the drum by opening the trap door or gate 38 while the latter is at the bottom of the drum.

What I claim is:

1. A separator comprising an approximately horizontal internally pocketed rotary drum having internal end contractions for holding the commingled separable mass against travel axially of the drum, and a hopper within said drum into which certain of the selected materials will be delivered by said drum.

2. A separator comprising an approximately horizontal internally pocketed rotary drum having internal end contractions for holding the commingled separable mass against travel axially of the drum, and a hopper within said drum into which certain of the selected materials will be delivered by said drum, said hopper having 110 a spout for delivery through one end of the drum.

3. A separator comprising an approximately horizontal internally pocketed rotary drum having internal end contractions for holding the commingled separable mass against travel axially of the drum, and a hopper within said drum into which certain of the selected materials will be delivered by said drum, said hopper having 120 a spout for delivery through one end of the drum, and the said drum at that end having an opening for the discharge of the rejected materials.

4. A separator comprising an approximately horizontal internally pocketed rotary drum having internal end contractions for holding the commingled separable mass against travel axially of the drum, and a hopper within said drum into which certain of the selected materials will be delivered by said drum, said drum having its support at one end and being removable from its support by movement away from the same and being replaceable by movements toward said support.
5. A separator comprising an approximately horizontal internally pocketed rotary drum having internal end contractions for holding the commingled separable mass against travel axially of the drum, and a hopper within said drum into which certain of the selected materials will be delivered by said drum, said drum and hopper having their supports at one end of said drum and both being removable by movements away from said supports and being replaceable by movements toward said supports.
6. A separator comprising an approximately horizontal internally pocketed separating drum rotatively supported at one end and open at its other end, and a hopper located within said drum and supported from the closed end of the drum but restrained against rotation with the drum.
7. A separator comprising an approximately horizontal internally pocketed separating drum rotatively supported at one end and open at its other end, and a hopper located within said drum and tiltably supported adjacent the closed end of the drum but restrained against rotation with the drum.
8. A separator comprising an approximately horizontal internally pocketed separating drum rotatively supported at one end and open at its other end, and a hopper located within said drum and supported adjacent the closed end of the drum but restrained against rotation with the drum, the said drum at its open end having a contracted annular flange.
9. A separator comprising an approximately horizontal internally pocketed separating drum rotatively supported at one end and open at its other end, and a hopper located within said drum and supported adjacent the closed end of the drum but restrained against rotation with the drum, said drum at its open end having an outwardly converging truncated conical flange.
10. A separator comprising an approximately horizontal internally pocketed separating drum rotatively supported at one end and open at its other end, and a hopper located within said drum and supported adjacent the closed end of the drum but restrained against rotation with the drum, the said drum at its open end having a contracted annular flange, and the said hopper having a discharge spout extended outward through the contracted opening afforded by said annular flange.
11. A separator comprising an approximately horizontal internally pocketed separating drum rotatively supported at one end and open at its other end, and a hopper located within said drum and supported adjacent the closed end of the drum but restrained against rotation with the drum, said hopper having a discharge spout provided with a normally closed gate.
12. A separator comprising an approximately horizontal internally pocketed rotary separating drum, and a hopper located within said drum, said drum and hopper being arranged for tilting movements to discharge their contents at the same downwardly pressed ends.
13. A separator comprising an approximately horizontal internally pocketed rotary drum having an internal end contraction for holding the commingled separable mass against travel axially of the drum, and a hopper within said drum into which certain of the selected materials can be delivered by said drum, and the said drum at that end having an opening for the discharge of the rejected materials.
14. A separator comprising an approximately horizontal internally pocketed separating drum, and a non-rotary hopper located within said drum, said drum and hopper being supported at one end and arranged for discharge at the opposite ends, said drum and hopper being arranged for common tilting movements to discharge their contents.
15. A separator comprising a relatively fixed support, a weighted supporting lever pivoted to said support, an internally pocketed separating drum journaled to said lever on an axis extended longitudinally thereof and extending in a direction away from the weighted end of said lever, a non-rotary hopper within said drum also supported from said lever, said drum being open at its extended end and said hopper having a discharge spout arranged to deliver through the open end of said drum.
16. A separator comprising a relatively fixed support, a weighted lever pivoted to said support and provided with a longitudinal spindle extended in a direction away from its weighted end, an internally pocketed separating drum open at one end and at its other end provided with a hub journaled on said spindle, a hopper within said drum mounted on said spindle and thereby held against rotation with the drum, said hopper being arranged to discharge through the open end of said drum.

In testimony whereof I affix my signature.
CLARENCE W. CARTER.
